(57) **CLAIM**

The ornamental design for a candy dispenser machine as shown.

DESCRIPTION

FIG. 1 is a perspective view of a candy dispenser machine showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view of the candy dispenser machine shown in FIG. 1 shown in a condition of use; and, FIG. 9 is an exploded view of the candy dispenser machine shown in FIG. 1.

The broken lines showing a candy jar in FIG. 8 depict environmental subject matter and from no part of the claimed design. The remaining broken lines showing the figures depict portions of the candy dispense machine that form no part of the claimed design.

1 Claim, 9 Drawing Sheets
